UNITED STATES PATENT OFFICE.

FREDERICK H. COWLES, OF NEW YORK, N. Y.

HANGER FOR TROUSERS OR SKIRTS.

SPECIFICATION forming part of Letters Patent No. 723,587, dated March 24, 1903.

Application filed December 19, 1901. Serial No. 86,593. (No model.)

To all whom it may concern:

Be it known that I, FREDERICK H. COWLES, of the borough of Manhattan, city, county, and State of New York, have invented a new and useful Improvement in Hangers for Trousers or Skirts, of which the following is a specification.

My improvement consists in a rod extended back and forth in a horizontal or approximately horizontal plane, with parallel or approximately parallel portions in close proximity, the ends being extended upwardly to serve as connections with any suitable support.

15 In the accompanying drawings, Figure 1 is a top view of an article embodying my improvement. Fig. 2 is a front view of the same.

Similar letters of reference designate corresponding parts in both figures.

A designates a rod extended back and forth, so as to have a number of parallel portions $a' a^2 a^3 a^4 a^5 a^6 a^7 a^8 a^9$, with intermediate junctional portions $a^{10} a^{11} a^{12} a^{13} a^{14} a^{15} a^{16} a^{17}$. I 25 deem it preferable to construct this of a straight metal rod and produce the desired formation by bending the same. Thus made it will be resilient, and resilience is a matter of importance. I do not, however, wish to be confined to any special material. The spaces between the portions $a' a^2 a^3 a^4 a^5 a^6 a^7 a^8 a^9$ have openings $a^{18} a^{19} a^{20} a^{21} a^{22} a^{23}$ alternately at opposite sides of the article. The extreme ends $a^{24} a^{25}$ are bent upwardly, and the end 35 a^{25} is extended rearwardly to the plane or substantially the plane of the end a^{24} and

then bent upward again, so that both ends may be fastened to a common support. Means for fastening them to a support may advantageously consist of screws, and therefore 40 screw-holes a^{26} are provided.

It will be seen that all parts of the article are in approximately the same horizontal plane except the ends, which are in approximately the same vertical plane. It will also 45 be observed that the portions $a' a^2 a^3 a^4 a^5 a^6 a^7 a^8 a^9$ are substantially parallel.

By the terms "parallel" or "substantially parallel" when speaking of the portions $a' a^2$, &c., I mean portions the garment-supporting surfaces of which are in parallel straight lines.

What I claim as new, and desire to secure by Letters Patent, is—

A hanger for garments, consisting of a rod 55 constructed at one end for attachment to a support, and extending thence vertically, thence substantially horizontally and back and forth substantially horizontally to form substantially parallel portions adapted to 60 coact to receive and hold between them a garment, thence upward and rearwardly, and terminating in an end portion constructed for attachment to a support.

In testimony whereof I have signed my 65 name to this specification in the presence of two subscribing witnesses.

FREDERICK H. COWLES.
